UNITED STATES PATENT OFFICE.

RUTH E. HARRIS AND ROY L. CHANCE, OF SAN FRANCISCO, CALIFORNIA.

DESIGN FOR A SALT AND PEPPER BASKET.

54,916.

Specification for Design.

Patented Apr. 20, 1920.

Application filed February 11, 1920. Serial No. 359,458. Term of patent 14 years.

To all whom it may concern:

Be it known that we, RUTH E. HARRIS and ROY L. CHANCE, citizens of the United States, residing in the city and county of San Francisco and State of California, have invented a new, original, and ornamental Design for a Salt and Pepper Basket, of which the following is a specification, reference being had to the accompanying drawing, forming part thereof.

The figure is a perspective view of a salt and pepper basket, showing our new design.

We claim:

The ornamental design for a salt and pepper basket, as shown.

RUTH E. HARRIS.
ROY L. CHANCE.
